UNITED STATES PATENT OFFICE

2,688,194

APPARATUS FOR INDEXING MATS USED IN
THE COLOR PRINTING ART

Charles A. Jordan, Buffalo, N. Y., assignor to Buffalo Colorpress, Inc., Buffalo, N. Y., a corporation of New York

Application August 13, 1952, Serial No. 304,071

8 Claims. (Cl. 33—184.5)

1

This invention relates to the art of color printing and more particularly to a machine for indexing the mats used for forming the various printing plates so that when these plates print in their respective colors the final printed sheet has the colored areas in proper registry.

In color printing, the sheet of paper is successively brought in printing contact with a plurality of printing plates each of which applies one color. In the color printing art, it is common practise to employ four separate plates one for each of the colors yellow, blue, red and black. It is readily apparent that these plates must be formed so that when set up in a conventional printing press the respective colored areas printed by these plates register as intended.

By way of background, the artist designs the subject matter and coloring therefor to be printed. Then a mat is produced for each color to be printed, such as yellow, blue, red and black previously mentioned. With such a color combination, four mats are necessary for each subject matter to be color printed whether it is of a size to cover a full page or only a portion thereof. These mats are used as forms to cast printing plates. The printer usually receives the set of mats from a supplier and casts his own plates from these mats. Heretofore considerable time has been consumed and difficulty experienced in positioning the mats individually in a casting box so that when the printing plates are cast, finished and mounted on the roll of a conventional printing press, the indicia on the various plates are registered or relatively physically oriented such that the colored areas printed are in proper registry and do not overlap. This has increased the make ready time and hence the expense of the printing job.

The principal object of the present invention is to provide a machine which indexes the mats in a given set of the same so that each mat can be placed in the proper position in the casting box without relying on the skill of a workman to properly position the mat preparatory to casting.

Another important object is to provide such a machine which indexes each of the mats in a set in a rapid and facile manner so that make ready time is greatly reduced resulting in savings in time and labor costs.

Another object is to provide such a machine which is simple in construction, easy and rapid to operate, relatively inexpensive, sturdy and not likely to get out of order or require repairs.

Other objects and advantages of the invention

2

will be apparent from the following description and accompanying drawings in which:

Fig. 1 is a top plan view of a mat prepared for indexing by a machine embodying my invention.

5 Figs. 2 and 3 are enlarged fragmentary sectional views thereof taken on the correspondingly numbered lines of Fig. 1.

Fig. 4 is an elevational view of the front of a machine embodying my invention, with some 10 parts shown in section.

Fig. 5 is a top plan view thereof with portions broken away to reveal parts of the machine.

Fig. 6 is an enlarged fragmentary vertical sectional view thereof taken generally on line 6—6, 15 Fig. 5.

Fig. 7 is a fragmentary vertical sectional view thereof taken on line 7—7, Fig. 6.

Fig. 8 is an enlarged fragmentary vertical sectional view thereof taken generally on line 8—8, 20 Fig. 5.

Fig. 9 is a fragmentary vertical sectional view thereof taken on line 9—9, Fig. 8.

Fig. 10 is an enlarged fragmentary vertical sectional view through the pointer head assembly 25 shown at the left of Fig. 9.

Fig. 11 is a vertical transverse sectional view thereof taken on line 11—11, Fig. 10.

Fig. 12 is an enlarged fragmentary vertical sectional view of the clutch assembly shown in 30 Fig. 4 and taken generally on line 12—12 thereof.

Fig. 13 is a transverse vertical sectional view thereof taken on line 13—13, Fig. 12.

Fig. 14 is a perspective diagrammatic view of the mat shown in Fig. 1 and representing a typical positional relation of the primary and secondary pointers of my novel machine to this mat and also showing the mat provided with the indexing markings applied by the machine.

Fig. 15 is a perspective view of a mechanical shear, partly in section and schematic, and showing on its table a mat with indexing markings provided by my novel machine, positioned to be trimmed along a longitudinal side.

40 Fig. 16 is a view similar to Fig. 15 but showing the mat in position to be trimmed along a transverse end.

Fig. 17 is a fragmentary sectional view of the mechanism for selectively lifting and lowering the index pins shown in Figs. 15 and 16, this view 45 being taken generally on line 17—17 of Fig. 16.

Fig. 18 is a top plan view of a casting box in open position and showing a mat, provided with index markings provided by my novel machine and trimmed, arranged in the box.

55 Fig. 19 is an enlarged fragmentary transverse

sectional view thereof taken on line 19—19, Fig. 18.

Figs. 20 and 21 are respectively enlarged fragmentary transverse and longitudinal sectional views thereof taken on the correspondingly numbered lines of Fig. 18.

The underlying principle of my machine for indexing each mat of a series of the same required for color printing of a given subject matter, is to determine the imaginary centerlines of the effective printing area of each mat as a whole in two directions perpendicular to each other so that the location of the imaginary center of such area is determined, and to provide each such mat with indexing markings related in the same manner to such imaginary center and centerlines. The indexing markings of each mat in a color series can then be utilized to arrange the mats individually and successively in proper position in a conventional casting box modified only slightly to provide mechanical elements for cooperating with the indexing markings whereby proper registry of the printing plates is assured.

As is well known, a mat used in color printing is a pressed fiber sheet formed with raised and recessed areas in accordance with the design and coloring of the subject matter to be printed on the finished paper sheet. A separate mat is provided for casting a printing plate for each color to be applied. Each mat is intended to be placed against the semi-circular face of a casting box and molten metal, usually a lead nickel alloy, allowed to flow over the exposed portion of the mat so as to reproduce the indicia of the mat in the printing or external face of the semi-circular printing plate so cast. The mats in a given set are suitably individually produced so that if the printing plates made therefrom are properly oriented on the rolls of a conventional printing press, the various colors will be in their intended registry. The present invention is not concerned with the production of such sets of mats which is well known to those skilled in the art, but rather with the indexing of the mats in a given set so that the printing plates formed therefrom will be in registry.

A typical mat as received from a supplier is illustrated in Fig. 1 and is represented by M. This mat may be considered as any one of the set necessary for the various colors to be printed. As shown this mat has an effective printing area A defined by the spaced horizontally extending raised ribs 25, 26 and the spaced vertically extending raised ribs 27, 28, which ribs are integrally joined at their meeting ends and circumscribe the rectangular area A. In an actual mat, this printing area A would include indicia which has been omitted from the illustration in Fig. 1 since this varies with the subject matter to be printed, although raised indicia are suggested at 29. As shown in Figs. 2 and 3, the raised ribs 26 and 27 are lands formed from the body of the sheet material used to produce the mat. The mat is usually provided with liberal perimetral margins, shown in Figs. 1-3 as including inner and outer margins 30, 31 respectively. These margins are shown as offset one from the other but still below the level of the upper surfaces of the raised ribs 25—28. Generally the mat is trimmed along the boundary line between the inner and outer margins 30, 31 so that the mat will fit into a semi-circular casting box.

Preparing mat for indexing (Figs. 1-3)

In preparing the mat for indexing on the ma-

chine embodying my invention, the rectangular effective printing area A is bisected along each of three sides. For example, referring to Fig. 1, the horizontal distance between the two points P₁ and P₂, which lie respectively along the inner edges of the vertical raised ribs 27, 28 and equally spaced from the inner edge of the lower horizontal raised rib 26 so that the measurement is parallel to the same, is divided in half to locate the center point P₃. A small mark or indentation is made on the mat at this center point P₃. In a similar manner the center point P₄ is determined in a direction along the left vertical raised rib 27 between the end points P₅ and P₆; and the center point P₇ between the end points P₈ and P₉ along the right vertical raised rib 28. The center points P₃, P₄, P₇ may be located in any suitable manner as by measuring with a scale the distance between the respective end points and halving such distance, or by using a bisecting pair of dividers, or even such center points may be on the mats as originally received from the supplier of the same. It will be seen that an imaginary horizontal centerline L_h connecting the center points P₄, P₇, when perpendicularly intersected by an imaginary vertical centerline L_v extending through the center point P₃, would locate an imaginary center C for the rectangular area A.

Each mat in a given color set will have formed therein the raised border ribs 25—28 of the same length and spaced between opposing pairs of the same as is shown in Fig. 1. In other words, the effective printing area of each mat is the same. Therefore with the practise of my invention it is essential to locate the imaginary center C of each mat of a set and to index each mat with respect to such imaginary center and the imaginary centerlines L_h, L_v passing therethrough.

Indexing machine (Figs. 4-13)

The machine for so indexing the mats and forming the subject of the present invention is shown in Figs. 4-13. Referring to Fig. 4, the machine is shown as having a cabinet-like frame including vertical left and right side panels 35 and 36 respectively, a rear panel 37, and a front panel 38. These panels support a flat horizontal plate 39 of generally rectangular outline, as shown in Fig. 5, which provides a table on which a mat can be placed for indexing the same. The mat is held flat and immovable to this surface by suction. For this purpose, the table plate 39 has a multiplicity of holes 40 arranged over substantially its full area (Fig. 5) to form a working area, and these holes communicate with a suction chamber 41 extending along the bottom of the table plate. The bottom of this suction chamber 41 is enclosed by a horizontal plate 42 which is joined along its perimeter to the various panels of the machine frame. Suction is applied to the chamber 41 through a pipe 43 connected at one end to the plate 42 and at its other end to a vacuum pump 44 of any suitable type. This pump is shown as mounted on a shelf 45 of the machine frame which shelf also supports an electric motor 46. This motor drives the vacuum pump 44 through a belt 48. A master switch (not shown) for turning the motor 46 on and off is preferably provided.

Suction can be selectively applied to the suction chamber 41 and to this end the pipe 43 is provided with a suitable valve 49 (Fig. 4) operated under control of the lever 50 (Fig. 5) shown as extending outwardly slightly from the front side of the machine. When the valve 49 is closed the

pump 44 is connected with the suction chamber 41, but when opened by manipulating the lever 50 the pump is bypassed to the atmosphere and thereby disconnected from this chamber.

Power actuated means are provided for making indexing markings on a mat arranged in suitable position on the table plate 39. Such means are shown as including two punches 52 and 53 (Fig. 4) and a marker 54 (Fig. 6). All three marking devices are disposed above the table plate 39 and operatively arranged for being moved vertically downwardly toward this plate so as to apply indexing markings to a mat arranged thereon. The punches 52, 53 are shown as arranged in line with each other along the transverse centerline X—X of the table plate 39 (Fig. 5) and adjacent opposite ends thereof with the punch 52 at the left and the punch 53 at the right as shown in Figs. 4 and 5. The marker 54 is shown as arranged adjacent the rear of the machine and in line with the centerline Y—Y of the table plate 39 running from front to rear of the machine. The machine centerlines X—X, Y—Y are perpendicular to each other and intersect at point D (Fig. 5) with the centerline Y—Y bisecting the distance between the opposing side surfaces of the punches 52, 53. Point D is therefore the center of the working area of the table plate 39 and the imaginary center of a mat, such as the center C of the mat M shown in Fig. 1, must be registered with the center D of the table plate working area, as well as the mat centerlines L_h and L_v being aligned with the machine centerlines X—X, Y—Y respectively, before the mat is indexed by the punches 52, 53 and marker 54, as later described herein.

The punches 52 and 53 are a fixed distance apart whereas the marker 54 can be adjusted along the machine centerline Y—Y toward or away from the transverse machine centerline X—X on which the punches are located. The operative lower end of punch 53 is circular in cross section so as to punch a round hole whereas the operative lower end of punch 52 is elongated with rounded ends so as to punch a slot-type hole. Except for these differences, the punches 52, 53 and their supports and operating mechanisms are identical. Hence only a detailed description of one will be made.

Each of the punches 52, 53 is slidably mounted for vertical movement on a horizontal arm 56 extending inwardly from a bracket 57 suitably mounted on the table plate 39 adjacent the lateral end thereof. A pair of spaced ears 58 extend upwardly from the arm 56 on opposite sides of the punch 52 or 53 and serve as journals for a horizontal shaft 59. An eccentric cam 60 is fast to this shaft and arranged between the ears 58 and works on a seat 61 provided on the upper end of the punch (Fig. 8). Each punch is shown as biased upwardly by a helical compression spring 62 interposed between the corresponding arm 56 and a lateral extension 63 on this punch, as shown for the punch 53 in Fig. 8.

Each cam shaft 59 is shown as driven by similar means which include a bevel gear 64 fast to this shaft adjacent its outer end, in turn driven by a bevel gear 65 fast to the upper end of a vertical jack shaft 66 which has another bevel gear 67 fast to its lower end, a bevel gear 68 mating therewith mounted on the end of a horizontal cross shaft 69. The corresponding pairs of gears 64, 65 and 67, 68 are arranged in housings 70 and 71 respectively which also serve as journals for the corresponding ends of the shafts on

which these gears are mounted. The housing 70 is shown as mounted on the upper end of a vertical bar 72 extending upwardly from the machine frame along the side thereof, and the housing 71 as mounted on the side panel of the machine. A horizontal bar 73 connects the two gear housings 70 on opposite sides of the machine.

Returning to the mechanical drive, the horizontal cross shaft 69 is shown as having a bevel gear 74 connected thereto intermediate its ends and additionally journalled on one flange of an angle bracket 75 depending from the lower horizontal plate 42 (Figs. 4 and 12). The gear 74 meshes with another bevel gear 76 fast to the front end of a horizontal clutch shaft 78 which extends in a direction fore-and-aft of the machine. The front end of this clutch shaft 78 is journalled on the other flange of the angle bracket 75 and its rear end is suitably journalled on the rear panel 37 of the machine frame, as shown in Fig. 12. The clutch shaft carries a one-revolution clutch indicated at 79 which may be of any suitable construction. This clutch is actuated by a lever 80 pivotally mounted on the bracket at 81 and this lever is shown as manipulated by a hand lever 82 arranged on the front of the machine frame (Fig. 5). The clutch 79 is driven by a pulley 83 which in turn is driven by another but smaller pulley 84 through a belt 85 which passes around these pulleys. The pulley 84 is fast to a countershaft 86 suitably journalled on the machine frame and to which a larger pulley 88 is also fast. A belt 89 from the motor 46 drives the pulley 88.

The marker 54 is slidably mounted for vertical movement on a slide 92 which is movable along a horizontal bar 93 as shown in Figs. 6 and 7. This bar 93 extends in a fore-and-aft direction of the machine parallel to and above the fore-and-aft centerline Y—Y of the table plate working area. At its rear end the bar 93 is rigidly connected to an upright 94 extending upwardly from the rear side of the machine frame and at its front end this bar is shown as rigidly connected to a block 95 which in turn is rigidly connected to a horizontal bar 96. This bar 96 is spaced above the table plate 39 and extends across the full width thereof, being rigidly connected at its opposite ends to the vertical bars 72. This transverse bar 96 is parallel to the transverse centerline X—X of the table plate working area.

Referring to Fig. 7, the slide 92 is shown as embracing the bar 93 which is out of round in cross section to prevent relative turning between the slide and bar. Friction between the engaging surfaces of the slide 92 and bar 93 holds the former in any adjusted position along the latter although suitable locking means may be employed if desired. The marker 54 is shown as having its lower end tapered to provide a line edge 98 adapted to engage the upper surface of a mat and place a center mark on the same for a purpose hereinafter described. The line edge 98 is in vertical alignment with the fore-and-aft centerline Y—Y of the machine. The marker 54 is constantly urged toward an elevated position by a helical compression spring 99 arranged between the top of the slide 92 and a lateral extension 100 on the marker. The upper extremity of the marker is formed with a seat 101 which engages with an elongated eccentric cam 102. The stub ends 103, 104 of this cam 102 are suitably journalled in the block 95 and upright 94 respectively as shown in Fig. 6. The rear stub end 104 extends through the upright 94 and its

extremity has fast thereto a bevel gear 105 which meshes with another bevel gear 106 fast to the upper end of a vertical jack shaft 108 extending along the rear of the machine frame. This vertical shaft 108 is suitably journaled at its upper end in a housing 109, which also houses the bevel gears 105, 106 (Fig. 6), and at its lower end is suitably journaled in a housing 110. The lower extremity of the vertical shaft 108 has a bevel gear 111 fast thereto and this gear meshes with another bevel gear 112 fast to the rear end of the clutch shaft 78. The housing 110 also houses the bevel gears 111, 112.

It will therefore be seen that when the manual control lever 82 for the one revolution clutch 79 is swung so as to lift the clutch lever 80 the clutch is permitted to drive the clutch shaft 78 for one revolution, the control lever 82 being manually released in time to disengage the clutch after one revolution of the shaft. Turning of the clutch shaft 78 through the various gearing previously described also rotates the shafts 69, 66, 59, 108 thereby to rotate the eccentric cams 60 for the punches 52, 53 and the eccentric cam 102 for the marker 54. It is to be noted that when the cams 60 and 102 are at rest their salient part projects vertically upwardly so that the punches and marker are in their extreme elevated position. It is further to be noted that the marker 54 works in opposition to the table plate 39 whereas this plate has an insert 113 provided with a hole 114, as shown in Fig. 8, to receive the end of the corresponding punch. A discharge chute 115 is shown in Fig. 8 as arranged under the hole 114 to receive the slugs or cut outs stamped from the mat which is placed on the table plate 39. Such an insert and discharge chute are provided for each of the punches 52, 53.

So far, the indexing marking means have been described. The means for positioning or orienting the mat on the table plate 39, preparatory to marking, will now be described. As previously described, considering the mat M shown in Fig. 1, the imaginary centerline L_h of the mat must be aligned and superposed with the transverse centerline X—X of the table plate working area connecting the centers of the punches 52, 53. As well, the imaginary centerline L_v of the mat M must be aligned and superposed with the fore-and-aft centerline Y—Y of the table plate working area along which the marking edge 98 is rectilinearly movable. When this alignment of the mat and machine centerlines is effected the imaginary center C of the mat will register with the center D of the table plate working area. It is only after a mat has been so oriented or positioned that the punches 52, 53 and marker 54 are actuated.

For so positioning the mat, three primary pointers 120, 121, 122 are provided and are adapted to be registered with the center points P₄, P₇, P₃ respectively of the mat M shown in Fig. 1. The pointers 120, 121 are arranged for horizontal movement along the transverse centerline X—X of the machine with the pointer 120 being adjacent the punch 52 and the pointer 121 being adjacent the punch 53. The pointer 122 is also arranged for horizontal movement but along the fore-and-aft centerline Y—Y of the machine.

Each of the pointers 120, 121 is shown as carried on a slide 123 which is slidably arranged in a slideway 124 provided on the front face of the transverse bar 96 as best shown in Figs. 4 and 6. The slides 123 and slideway 124 preferably have a dove tail connection as shown.

Referring to Fig. 6, the pointer 122 is shown as carried on the front end of a horizontal rod 125 which extends in a fore-and-aft direction of the machine parallel to the centerline Y—Y. This rod 125 is slidably arranged on the block 95 and upright 94 each of which carry a key 126. The keys 126 project into an elongated keyway 127 provided longitudinally in the rod 125 so as to prevent this rod from turning but yet permitting it to be moved in a longitudinal direction.

The pointers 120, 121, 122 are each mounted for vertical movement relative to their respective supports. Normally these pointers are held in an elevated position above the table plate but they can be individually and selectively released to a lowered position in which they are biased downwardly toward the table plate 39. Similar means are provided for each pointer for this purpose and the details of the same will be described only in connection with the pointer 122. Referring to Fig. 6, the pointer 122 is shown as embedded centrally in the lower end of a plunger 129 which is slidably arranged in a vertical tube 130. The upper end of this tube is closed by a removable plug 131 and a helical compression spring 132 is arranged within the tube between the opposing ends of the plug 131 and plunger 129. This plunger carries a laterally extending pin or handle 133 which projects through a bayonet type slot 134 provided in the tube 130 and having connected horizontal and vertical branches. It will be seen that with the pin 133 disposed in the vertical branch of the slot 134, the spring 132 expands to force the plunger 129 downwardly and thereby moves the pointer 122 toward the table plate 39 as shown in Fig. 6. When it is desired to raise the pointer, the pin 133 is lifted and turned laterally into the horizontal branch of the slot 134 which locks the pointer in an elevated position. The tube 130 is shown as mounted to a bracket 135, in turn secured to a block 136 by screws 137. The block is suitably rigidly connected to the front end of the rod 125.

The means for vertically moving the pointers 120, 121 are similar to those described for the pointer 122 and hence the same reference numerals have been applied, although it is to be noted that the tubes 130 and the plungers internally arranged therein for the pointers 120, 121 are shorter so that the upper ends of these tubes do not interfere with the rod 125 or arms 56, as shown in Fig. 6.

The machine is also shown as provided with a set of three secondary pointers 139, 140, 141 (Figs. 4, 5). Each of these secondary pointers is adjustably mounted for movement to various selected locations over the working area of the table plate 39 and for a purpose hereinafter described.

The adjustable support means for each of the secondary pointers 139, 140 are identical and hence only that for the pointer 140 shown in Fig. 8 will be described. Each of the horizontal arms 56 overhanging the table plate is provided with a horizontal guideway 142 on its front face (Fig. 4). A slide 143 is slidably arranged in each such guideway 142 and these parts preferably have a dovetail connection. Each slide 143 may be maintained in any adjusted position along its guideway by tightening a set screw 144. That end of each slide 143 toward the center of the machine is shown as formed to provide an enlarged head 145 which projects laterally from the slide toward the front of the machine (Fig. 8). This head

145 has a square hole 146 extending vertically through it to guidingly receive a screw 147 having four flat sides which are slidable along the walls of the square hole 146. The head 145 is slotted between the ends of its vertical hole 146 as indicated at 148 in Fig. 8 to provide opposing flat vertically spaced horizontal walls. A flat nut 149 is arranged in the slot 148 and threadedly connected to the screw 147, the vertical thickness of the nut being such as to closely fit the walls of the slot. The nut 149 is disk-like and of a large enough diameter so that its periphery which is preferably knurled projects laterally outwardly beyond the sides of the head 145. Thus by turning the nut 149 the screw 147 which cannot turn may be adjusted up or down as desired.

The lower end of the vertical screw 147 is suitably rigidly connected to the rear end of a forwardly projecting horizontal arm 150. This arm 150 is preferably uniformly square in cross section along its full length as shown in Fig. 9 to serve as a bar on which a slide 151 is slidably mounted and held in any desired adjusted position therealong by a set screw 152. The slide 151 which is in the form of a block having a square hole through which the arm 150 extends, has a depending lower portion provided with a horizontal transverse hole 152 extending therethrough. A screw 154 similar to the screw 147 is slidably arranged in the hole. A nut 155 similar to the nut 149 is arranged on the screw 154 and partially within a slot provided in the slide 151. Thus by turning the nut 155 the screw can be moved perpendicularly to the arm 150.

Referring to Figs. 9-11, one end of each screw 154 is shown as reduced and externally threaded as indicated at 156 to receive an internally threaded collar 157 which is in the form of a disk and screwed up tight against the shoulder formed on the end of the screw 154. A flat plate 158 fits against the outer face of the collar 157 and is held thereagainst by a screw 159 passing through a hole in the plate and having its inner end threadedly received in the screw 154. A recess 160 in the plate 158 and opening to that face thereof which engages the collar 156, houses a wind up spring 161. This spring surrounds the screw 159 and has one end suitably anchored to the plate 158 and the opposite end suitably anchored to the collar 157 as shown in Fig. 10. The spring 161 operates to urge the plate 158 to turn in a counterclockwise direction relative to the collar 156 as viewed in Fig. 11 and about the axis of the screw 159. The lower portion of the plate 158 is provided with a square hole extending transversely of the axis of the screw 159 and an arm 163, also square in cross section, is slidably arranged in this hole. The arm 163 extends in a direction parallel to the horizontal arm 150 and can be held in any desired adjusted longitudinal position relative to the plate 158 by the set screw 164. The rear end of the arm 163 is shown in Fig. 8 as holding the pointer 140 which depends therefrom.

Even though the spring 161 is arranged to urge the pointer 140 downwardly toward the table plate 39, it is desired that the pointer 140 be normally held in an elevated position as represented by broken lines in Fig. 8. This is accomplished by providing detent means between the plate 158 and collar 157. Referring to Figs. 10 and 11, such means includes a spring loaded ball 165 carried by the inner face of the plate 158 and adapted to be received in a semi-spherical

recess 166 provided in the opposing face of collar 157. Thus when the ball 165 is opposite the recess 166 and projects into the same, the arm 163 is held in the elevated position shown by broken lines in Fig. 8 but by merely depressing this arm to the full line position shown the ball 165 against the urging of its spring is forced to leave the recess 166 and rides on the flat face of the collar 157 while the wind up spring 161 expands to urge the pointer 140 downwardly. In this latter condition of the parts, the position of the detent ball is represented by broken lines at 165' in Fig. 11.

The third secondary pointer 141 projects downwardly from the rear end of an arm 168 which is similar to the arms 163 for the other secondary pointers 139, 140. Referring to Fig. 6, this arm 168 is adjustably mounted on a holder similar to the plate 158 shown in Figs. 9 and 10 and this holder has the same detent means shown in Figs. 9-11 for normally supporting the arm in an elevated inoperative position but permitting the arm to be released and urged downwardly toward the table plate. Hence this construction has not been reillustrated in connection with the arm 168 and the same reference characters have been employed to indicate like parts. The only difference is that the disk-like collar 157 in Fig. 6 is shown as being suitably connected to one end of a block 169 which adjacent its opposite end is provided with a vertical square hole which slidably receives a vertical bar 170, square in cross section. The connection between the block 169 and vertical bar 170 is maintained in any relative adjustment of these parts by a set screw 171 as shown in Fig. 4.

The upper portion of the vertical bar 170 extends through a square hole provided in a head 172 and held in any adjusted position relative thereto by a set screw 173. The head 172 is also formed to provide a horizontal square hole to one side of its vertical square hole and this horizontal hole slidably receives a horizontal bar 174, square in cross section. The head 172 is maintained in its desired adjusted position on the bar 174 by a set screw 175. This horizontal bar 174 projects forwardly from the transverse horizontal frame bar 73 and is adjustably mounted on the latter for movement longitudinally thereof. For this purpose the rear end of the movable horizontal bar 174 is suitably rigidly connected to a slide 176 which embraces the transverse horizontal frame bar 73 and is slideable therealong and can be held in any desired position longitudinally thereon by a set screw 177.

Fine adjustments of the slide 176 can be obtained by the following means. Adjacent to and independent of the slide 176 is an auxiliary slide 180, also embracing the transverse horizontal frame bar 73, as shown in Figs. 4 and 5. This auxiliary slide is movable along the bar 73 but can be made fast thereto by a set screw 181. A horizontal screw 182 fast at one end to the slide 176 projects through a hole provided in the auxiliary slide 180 and a nut 183 works on this screw. The nut 183 is arranged in a recess provided within and opening to one side of the auxiliary slide 180 and is constrained by the opposing walls thereof against movement relative thereto along the axis of the screw 182. The periphery of the nut 183 projects outwardly from the body of the auxiliary slide and is preferably knurled for easy manipulation. Thus with the set screw 181 tightened to hold the auxiliary slide immovable

and the set screw 177 loosened to render the main slide 176 movable, the nut 183 may be turned so as to adjust the relative spacing between these two slides and therefore permit of fine adjustment of the main slide 176 longitudinally of the horizontal frame bar 73. Of course, with both set screws 177 and 181 loosened the two slides 176 and 180 can be shifted along the bar 73 as a unitary structure.

Operation of indexing machine

Preparatory to operation of the indexing machine, the primary pointers 120, 121, 122 are checked to be sure each is locked in its elevated position. This is done by placing the pin 133 associated with each primary pointer 120, 121, 122 in the horizontal branch of the bayonet type slot 134 in the respective tube 130 (Fig. 6). Likewise, the arms holding the secondary pointers 139, 140, 141 are examined to be certain each is in its elevated position, normally held there by its respective detent means 165, 166 shown in Figs. 10 and 11. With all primary and secondary pointers raised there is clearance to slide a mat on the table plate 39.

Thereafter the electric motor 46 is turned on and the control lever 50 for the vacuum by pass valve 43 is positioned so that suction is not established in the suction chamber 41. Also the control lever 82 is in a position to render the one revolution clutch 79 inoperative.

The mat M shown in Fig. 1 is then placed face up with the center points P₃, P₄ and P₇ exposed on the table plate 39 of the machine by sliding it under the raised pointers. The mat M is then shifted on the table plate to register the center points P₄, P₇ and P₃ with the primary pointers 120, 121, 122 respectively. In doing this one of the primary pointers, say the primary pointer 122, is first lowered to engage the center point P₃. Then the mat is swung about this point contact to register the primary pointers 120, 121 with the center points P₄, P₇ respectively, and these pointers are lowered in turn to engage their respective center points on the mat. The lowered positions of the primary pointers are diagrammatically illustrated in Fig. 14. In registering the primary pointers 120, 121, 122 with the respective center points P₄, P₇, P₃, the mountings for these pointers are adjusted or shifted along their respective supports to permit the necessary three point contact with the mat center points. Thus the rod 125 supporting the primary pointer 122 can be shifted as desired along the fore-and-aft axis Y—Y of the machine, and the slides 123 carrying the primary pointers 120, 121 can be shifted individually along the slideway 124 on the transverse bar 96 and hence along the transverse axis X—X of the machine, as shown in Fig. 6. This adjustment of the movable supports for the primary pointers 120, 121, 122 and the mat M in order to bring these pointers into registry with the respective center points P₄, P₇, P₃ on the mat, takes only a few seconds. The primary pointers are individually lowered by swinging the respective pin 133 to aline the same with the vertical branch of the bayonet type slot 134 and these pointers are urged into firm contact with the mat by their respective springs 132, as shown in Fig. 6.

With all three primary pointers lowered in any order desired and engaging their respective center points on the mat it is evident that the mat has been oriented such that its imaginary centerline L_h is alined with the transverse center-

line X—X of the table surface 39 and the imaginary centerline L_v of the mat is alined with the fore-and-aft centerline Y—Y of the table surface so that the mat center C is superposed with the center D of the table working area.

After the mat M has been so centered, suction is applied to the holes 40 in the table plate 39 so as to firmly hold the mat in this centered position. This is accomplished by manipulating the control lever 50 so as to connect the suction pump 44 with the suction chamber 41. Utilization of suction to hold the mat in position avoids relying solely on the primary pointers for this purpose and accidental or unintentional displacement of the mat from its centered position is also minimized. Suction also maintains the mat flat.

Thereafter each of the secondary pointers 139, 140, 141 is in any order desired adjusted to register with a register or reference mark on the particular mat being processed which mark is common to all the other mats in the set to be indexed. Such register marks are usually a dot or cross formed as an integral part of the mat, either as a depression or a raised element, at different locations over the face of each mat, but all mats in a given set have register marks in corresponding locations. Instead of a predetermined register mark, a reference point for each of the secondary pointers may be selected as a part of the indicia of one mat which is common to the other mats in the set. Typical register marks are shown on the mat M at R₁, R₂, R₃, with R₁ being located slightly to the right and below center point P₄, with R₂ to the left and below center point P₇, and with R₃ to the right and above center point P₃. In Fig. 14, the registry of the secondary pointers 139, 140, 141 with the register marks R₁, R₂, R₃ respectively, is illustrated. It is to be specifically understood that each mat in a given color set has register marks corresponding to R₁, R₂, R₃ for the mat M shown in Figs. 1 and 14. It is also pointed out that the register marks for different sets of color mats may be different but they are the same for a given set.

Each of the secondary pointers 139, 140, 141 is lowered to engage its respective register mark R₁, R₂ or R₃ after the mountings for these pointers have been adjusted or shifted on their respective supports to bring about registry.

Thus in adjusting the positions of the secondary pointers 139, 140 to bring them into registry with the register marks R₁, R₂ respectively, the companion slide 143 can be moved along its guideway 142 after first loosening the set screw 144 to roughly position these pointers transversely of the machine. The set screws 144 are then retightened (Figs. 4 and 8). Final fine horizontal transverse adjustments of the pointers 139, 140 can be made by turning the respective nuts 155 (Figs. 4 and 9). Adjustments of these pointers fore-and-aft of the machine can be effected by loosening the set screw 152 and shifting the companion slide 151 along the arm 150 to the position desired and thereafter the set screw 152 is retightened (Figs. 5 and 8). Also adjustments in this same direction can be made by loosening the set screw 164 and shifting arm 163 relative to the holder 158 and thereafter retightening this set screw (Figs. 8 and 9). Fine vertical adjustments of the arms 150 are made by turning the nuts 149 (Fig. 8).

The secondary pointer 141 can also be adjusted to a position in registry with the register mark R₃ on the mat. For horizontal adjustments of the same in a direction extending transversely of

the machine, the set screws 177 and 181 are first loosened and then the connected slides 176, 180 shifted along the upper transverse frame bar 73. For fine adjustments, the set screw 181 on the auxiliary slide 180 is tightened while leaving the set screw 177 for the main slide 176 loose, and then turning the nut 183 (Figs. 4 and 5). When the fine adjustment is completed the set screw 177 is tightened. For horizontal adjustments of the secondary pointer 141 in a fore-and-aft direction of the machine, this may be achieved by loosening the set screw 175 to permit the head 172 to be slid along the bar 174 and then retightening this set screw, and also by loosening the set screw 164 and shifting the arm 168 relative to the holder 158 and then retightening this set screw (Figs. 5 and 8). Vertical adjustment can be made by loosening the set screw 173 and then moving the vertical bar 170 up or down as desired relative to the head 172, and thereafter retightening the set screw 173.

The condition has now been reached where all the primary and secondary pointers are in registry with their respective predetermined positioning marks, as shown in Fig. 14. The mat M is then ready for index marking which consists in punching therein the round hole 185, the elongated hole 186, and applying thereto the line mark 187, also as shown in Fig. 14. The punch 53 makes the round hole 185, the punch 52, the elongated hole 186, and the marker 54 the line mark 187. These index markings are performed simultaneously by the operator moving the control lever 82 for the clutch 79 so as to lift the stop lever 80 and permit the clutch to be operative for one revolution, at the end of which the clutch is again rendered inoperative automatically. Through the mechanism previously described the punches 52, 53 and marker 54 are driven downwardly toward the mat to produce the index marking thereon and automatically return to their elevated positions.

Following this all of the primary pointers 120, 121, 122 and secondary pointers 139, 140, 141 are individually raised out of contact with the mat M. In the case of the primary pointers this is done by lifting the pins 133 and swinging them into the lateral branches of the slots 134. In the case of the secondary pointers this is merely done by tipping up the arms 163, 168 supporting the same and the detent means previously described will hold these arms in this tipped up position as shown by broken lines in Fig. 8. It is important that the adjustments of the support means for the secondary pointers are not disturbed. The control lever 59 for the suction by pass valve 49 is then manipulated so that this valve disconnects the suction pump 44 with the suction chamber thereby destroying the suction hold on the mat M and this mat now indexed is slid out from under the pointers and is ready for the next operation.

Before describing this, the disposition of the remaining mats in the color set to be indexed should be considered. Each of these remaining mats, which it will be remembered bears register marks R₁, R₂, R₃ in the identical relation to the imaginary centerlines of such mats as for the mat M, are placed one at a time on the table plate 39 of the machine for indexing. Each mat is oriented so that its register marks R₁, R₂, R₃ are in registry with the respective secondary pointers 139, 140, 141, and these pointers are lowered in succession as such registry is obtained. The suction control lever 59

is then moved to apply suction to the mat and thereafter the clutch control lever 82 is moved to actuate the clutch 79 for one revolution which actuates the punches 52, 53 and marker 54 to produce the indexing markings 185, 186, 187 on this mat. Following this the secondary pointers 139, 140, 141 are lifted out of engagement with the mat, the suction control lever is again moved to cut off the suction hold on the mat, and the mat is removed.

In this manner each of the mats in turn is indexed quickly. It is to be noted that only the first mat M had to be provided with the center points P₃, P₄, P₇ and the primary pointers 120, 121, 122 were used only on the first mat, being retained in their elevated positions while indexing succeeding mats in the set. In other words, the secondary pointers 139, 140, 141 are used only to determine the centered positions of the succeeding mats. If desired, each mat in a set could be provided with center points P₃, P₄, P₇ similar to those for the first mat M, and the primary pointers operated in connection therewith, but there would then be no need for the secondary points and, more important, considerable additional time would be required. Accordingly, it is preferred to follow the procedure first described.

As a result of the use of my novel indexing machine it will be seen that each mat in a given color set is provided with a pair of holes 185, 186 a predetermined distance apart, and preferably also a line mark 187 which if extended would bisect said distance, with these holes and mark on the imaginary centerlines of the effective printing area A of each mat. The line mark 187 may be in the nature of a score so as to be visible from opposite sides of the mat and also if desired the line edge 93 of the marker 54 may have a colored dye applied thereto, if desired, although means for doing this are not shown in the drawings. The sole advantage of making a colored line mark 187 is to render it more conspicuous.

Trimming of mat (Figs. 15-16)

After each mat is indexed as above described, the same is trimmed in order to fit it into the casting box shown in Figs. 18-21. The procedure is the same for each mat and hence will be described only in connection with the first mat M.

While the trimming and casting box operations form no part of the present invention, they are described to show the utility of indexing the mats.

The indexing markings 185, 186, 187 of the mat M shown in Fig. 14 are utilized in trimming this mat. As shown in Figs. 15-17, the numeral 190 represents the table of any suitable conventional mechanical shears having two retractable pins 191, 191 rising therefrom. Referring to Fig. 17, each pin 191 is urged downwardly by a spring 192 against a flat surface of a rotatable step cam 193. This cam is mounted on a shaft 194 turned by the handle 195. When the handles are in the position shown in Fig. 15, the pins 191 rest on the high steps of the cams 193 and project upwardly through the table but when these handles are in the down position shown in Fig. 16, the pins rest on the lower steps of the cams and are flush with the table.

The stationary blade of the shears is the rear edge of the table 190 and cooperates with a movable blade 196. The pins 191 are arranged on a line 197 parallel to and a predetermined dis-

15

tance from the rear edge of the shear table which line continues over end guides 198, 198 having opposing faces perpendicular to this line.

It is only necessary to trim the mat along the longitudinal side adjacent the line center mark 187 and the two shorter transverse ends. To trim the long side the mat M is placed so that the holes 185, 186 fit over the upstanding pins 191. The shear is then closed and cuts the mat along the line 198 which passes through the center mark 187 on the mat, as shown in Fig. 15. Thereafter the pins 191 are retracted and the mat is turned 90 degrees on the table so that the cut edge 199 is placed against one of the end guides 199. The center mark 187 on the mat is aligned with a second line 200 on the table which is spaced farther away a predetermined distance from the cutting line of the shears as shown in Fig. 16. Closing the shears trims the mat along a line just outside the hole 185. The mat is then turned 180 degrees and inverted so that the center mark 187 showing through the reverse side of the mat is aligned with the line 200 and abuts against the other end guide 198. Closing the shears trims the mat along a line intersecting the elongated hole 186 therein.

Placing mat in casting box (Figs. 18-21)

Figs. 18-21 illustrate a conventional casting box which includes a trough shaped mold 202 having a semi-cylindrical cavity and pivoted by hinges 203 to cooperate with the convex surface of an upright stationary mold (not shown). The mold cavity receives the mat M and to insure the proper positioning of the same therein, I have modified the mold 202 to the extent of providing two indexing pins on opposite sides of the mold and adjacent the longitudinal free edges thereof. One such indexing pin is indicated at 204 and the other at 205, and these pins are adapted to fit the holes 186 and 185 respectively in the mat.

Each of the indexing pins 204, 205 is retractable and for this purpose is shown as arranged on the inner end of a stem 206 projecting through a hole in the mold 202 and having a handle 207 on its outer end. The hub of the handle 207 is inclined along its inner face which cooperates with a stationary inclined face so that a camming action is achieved when the handle is turned to shift the stem 206 axially. A spring 208 is operatively arranged to urge the indexing pin to a projecting position as shown in Fig. 19.

The indexed and trimmed mat M is arranged on the indexing pins 204, 205 with the trimmed longitudinal edge 199 of the mat adjacent the hinges 203. This edge is covered by the usual curved foot stick 209 maintained in position on the mold 202 by abutments 209. The opposite untrimmed edge of the mat is covered by a sheet 210 of suitable material so that when the casting box is closed metal will not flow between the mat and the inner concave face of the mold 202. The trimmed short ends of the mat are covered by angle rails 211 hinged to the mold 202 and these rails cover the said ends of the mat as shown in Fig. 20. The rails are shown open in Fig. 18. When the casting box is closed and metal is run into the space between the mat and the stationary mold part (not shown), the metal abuts the axially facing edge of the foot stick 208 and the circumferentially facing edges of the rails 211 to form the printing plate 212.

Following casting, the casting box is opened, the rails 211 swung free, the foot stick 208 removed, the indexing pins 204, 205 retracted, and

16

the cast plate 212 is removed from the mold 202. The printing plate 212 is subsequently trimmed and processed in accordance with conventional procedures but these form no part of the present invention.

From the foregoing it will be seen that the present invention provides a machine for indexing mats used in color printing so that each mat can be placed in a casting box with assurance that the printing plates cast will be in proper registry with one another when mounted on the rolls of the printing press.

I claim:

1. Apparatus for indexing mats used in the color printing art to insure that printing plates made therefrom will be registered, comprising a table surface adapted to receive a mat thereon, a series of at least three pointers mutually spaced apart and arranged above said table surface and selectively lowerable for engaging predetermined center points arranged on the mutually perpendicular centerlines of a mat arranged on said table surface, means urging said pointers toward said table surface, releasable means arranged to hold said pointers in a retracted position away from said table surface against the urging of said last mentioned means, spaced punches arranged in a normally elevated position above said table surface and in a fixed spaced relation to each other, and power actuated means arranged to lower said punches simultaneously to form indexing holes in the mat.

2. Apparatus for indexing mats used in the color printing art to insure that printing plates made therefrom will be registered, comprising a table surface adapted to receive a mat thereon, a series of at least three pointers arranged above said table surface, two of which are arranged for movement along a rectilinear line and the third of which is movable along another rectilinear line which perpendicularly intersects said first mentioned line, means urging said pointers toward said table surface, releasable means arranged to hold said pointers in a retracted position away from said table surface against the urging of said last mentioned means, said pointers being selectively lowerable for engaging predetermined center points arranged on the mutually perpendicular centerlines of a mat arranged on said table surface, spaced punches arranged in a normally elevated position above said table surface and in a fixed spaced relation to each other, and power actuated means arranged to lower said punches simultaneously to form indexing holes in the mat.

3. Apparatus for indexing mats used in the color printing art to insure that printing plates made therefrom will be registered, comprising a table surface adapted to receive a mat thereon, a series of at least three pointers arranged above said table surface, two of which are arranged for movement along a rectilinear line and the third of which is movable along another rectilinear line which perpendicularly intersects said first mentioned line, means urging said pointers toward said table surface, releasable means arranged to hold said pointers in a retracted position away from said table surface against the urging of said last mentioned means, said pointers being selectively lowerable for engaging predetermined center points arranged on the mutually perpendicular centerlines of a mat arranged on said table surface, a pair of punches arranged a fixed distance apart on said first mentioned line and on opposite sides of said two pointers and normally in an elevated position above said table surface,

and power actuated means arranged to lower said punches simultaneously to form indexing holes in the mat.

4. Apparatus for indexing mats used in the color printing art to insure that printing plates made therefrom will be registered, comprising a table surface adapted to receive a mat thereon, a series of at least three primary pointers arranged above said table surface, two of which are arranged for movement along a rectilinear line and the third of which is arranged for movement along another rectilinear line which perpendicularly intersects said first mentioned line, means urging said primary pointers toward said table surface, releasable means arranged to hold said primary pointers in a retracted position away from said table surface against the urging of said last mentioned means, said primary pointers being selectively lowerable for engaging predetermined center points arranged on the mutually perpendicular centerlines of a mat arranged on said table surface, a plurality of secondary pointers each arranged over said table surface for selective adjustment in all horizontal directions to different locations, means urging said secondary pointers toward said table surface, releasable means arranged to hold said secondary pointers in a retracted position away from said table surface against the urging of said last mentioned means, said secondary pointers selectively lowerable for engaging predetermined register points on a mat arranged on said table surface, spaced punches arranged in a normally elevated position above said table surface and engageable with the marginal portion of a mat after the same has been properly positioned on said table surface, and power actuated means arranged to lower said punches simultaneously to form indexing holes in such mat.

5. Apparatus for indexing mats used in the color printing art to insure that printing plates made therefrom will be registered, comprising a table surface adapted to receive a mat thereon, a series of at least three primary pointers arranged above said table surface, two of which are arranged for movement along a rectilinear line and the third of which is arranged for movement along another rectilinear line which perpendicularly intersects said first mentioned line, means urging said primary pointers toward said table surface, releasable means arranged to hold said primary pointers in a retracted position away from said table surface against the urging of said last mentioned means, said primary pointers being selectively lowerable for engaging predetermined center points arranged on the mutually perpendicular centerlines of a mat arranged on said table surface, a plurality of secondary pointers each arranged over said table surface for selective adjustment in all horizontal directions to different locations, means urging said secondary pointers toward said table surface, releasable means arranged to hold said secondary pointers in a retracted position away from said table surface against the urging of said last mentioned means, said secondary pointers being selectively lowerable for engaging predetermined register points on a mat arranged on said table surface, a pair of punches arranged a fixed distance apart on said first mentioned line and on opposite sides of said two primary pointers and normally in an elevated position above said table surface and engageable with opposite marginal portions of a mat to punch holes therein when such mat is properly

positioned on said table surface, a marking member arranged in a normally elevated position on said other line and engageable with the marginal portion of such mat between the said opposite marginal portions thereof to apply a center mark to such mat, and power actuated means arranged to lower said punches and marking member simultaneously to engage such mat for the respective purposes stated.

6. Apparatus for indexing mats used in the color printing art to insure that printing plates made therefrom will be registered, comprising a table surface adapted to receive a mat thereon, a series of pointers arranged above said table surface and selectively movable theretoward for engaging predetermined positioning marks on a mat arranged on said table surface, indexing marking devices arranged above said table surface for reciprocal movement in a direction normal thereto, a rotatable cam associated with each of said devices and normally at rest in a position permitting the same to be in an elevated position above said table surface, spring means urging said devices to said elevated position, and power driven means arranged to rotate said cams simultaneously and including a selectively operable one revolution clutch whereby said devices are lowerable to engage a mat arranged on said table surface.

7. Apparatus for indexing mats used in the color printing art to insure that printing plates made therefrom will be registered, comprising a table surface adapted to receive a mat thereon, a plurality of pointers each arranged for selective adjustment to different locations over said table surface, manually releasable means holding each of said pointers in an elevated position above said table surface and comprising a pivotally mounted arm from one end of which the corresponding one of said pointers depends, spring means tending to pivot said arm to depress said pointer and detent means holding said arm in a tipped up position against the urging of said spring means, said detent means being released by manually depressing said arm so as to permit said pointer to engage a predetermined positioning mark on a mat arranged on said table surface, indexing marking devices arranged in a normally elevated position above said table surface, and means arranged to lower said devices into engagement with the mat.

8. Apparatus for indexing mats used in the color printing art to insure that printing plates made therefrom will be registered, comprising a table surface adapted to receive a mat thereon, at least three pointers above said table surface, independent means supporting said pointers for selective adjustment to different locations over said table surface, each of said means comprising a slide arranged above said table surface for horizontal movement transversely thereof, connected horizontal and vertical arms each adjustable as to its effective length to provide a support structure having one end mounted on said slide, a tip up arm connected at one end to one of said pointers which depends therefrom and pivotally mounted to the other end of said support structure, spring means tending to pivot said tip up arm to depress its pointer and detent means associated with the mounting of said tip up arm on said support structure and arranged to hold said tip up arm in a tipped up position against the urging of said spring means but releasable by manually depressing said tip up arm so as to permit its pointer to engage a predetermined

19

positioning mark on a mat arranged on said table surface, indexing marking devices arranged in a normally elevated position above said table surface, and means arranged to lower said devices into engagement with the mat.
